METHOD OF OPENING CANS

Charlotte A. Arnesen, Chicago, Ill.

Application February 8, 1939, Serial No. 255,303

6 Claims. (Cl. 30—15)

The invention pertains to a novel method of opening sheet metal cans used as containers for food products and other commodities, and having at least one end wall united to a cylindrical body 5 wall by means of a double interlocking seam, and has more especial reference to the opening of cans of the type shown in my copending application Serial No. 58,089, filed January 8, 1936, in which the seam is especially formed to provide 10 an annular space disposed externally of the can and fashioned to promote the circumferential severance of the seam by means of a cutting implement.

The primary object of the invention is to provide for the opening of a container by severing a 15 double interlocking seam and forming as an incident to the severance of the metal of a seam a removable friction slip cover for the container.

A further object is to provide for the severance of the seam externally of the can so as to form a removable slip cover and to effect simultaneously with the severance of the metal a circumferential expansion of the portion of the seam forming the skirt of the cover whereby to 20 facilitate removal of the cover.

The objects of the invention thus generally stated together with other and ancillary advantages are obtained by the construction and arrangement illustrated in the accompanying 25 drawing showing the invention in a preferred embodiment.

In the drawing:

Figure 1 is a fragmentary side elevational view of my improved container.

Fig. 2 is a fragmentary vertical sectional view showing one end portion of the container body and an associated end member in assembled relation but before being secured together.

Fig. 3 is a fragmentary sectional view illustrating the first step of the double seaming operation, the roller being shown partially in elevation.

Fig. 4 is a similar view showing the final seam sealing operation and illustrating the formation of an annular bead providing the aforesaid severing operation.

Fig. 5 is a side elevational view of a cutter applied to the container in position to perform the severing operation.

Fig. 6 is a fragmentary vertical sectional view taken approximately in the plane of line 6—6 of Fig. 5 but on a somewhat larger scale.

The novel method of opening cans is illustrated in connection with a container of the type shown and claimed in my said copending application 55 and comprising a cylindrical body 8 with end

members 9 (one only being shown) united with the body by means of seams 10 and 11. The bottom seam 10 may be of usual construction. The top seam 11, is a conventional upstanding double interlocking seam modified to facilitate the circumferential severance of the seam externally of the cylindrical body, and for this purpose the outer layer of the seam is fashioned so as to define an annular space adapted to receive the point of a cutting implement, so that in opening 10 the can it is only necessary to penetrate a single layer of metal without obstruction to the cutter from any other part of the seam.

Referring now to Fig. 4, a cutter-receiving space 13 is provided through the provision of an annular 15 bead 12 projecting radially from the bottom portion of the seam. The bead thus forms a downwardly facing shoulder 12a radially enlarged to facilitate engagement by the cutting edge of an implement bearing upon the upper edge of the 20 seam.

The can body is initially formed with an outwardly projecting flange 14, (Fig. 2) and the cover section 9 is formed with a central depression providing a vertical annular portion 15 of 25 an external diameter corresponding with the internal diameter of the can body. Projecting outwardly from the upper end of the annular portion 15 is a peripheral portion or flange 16 of a width substantially greater than the body flange 30 14 and terminating in a downwardly and inwardly turned curl 17. 18 designates the usual gasket of rubber composition or other suitable sealing material applied to the peripheral portion 16 of the end member, this gasket being 35 omitted from Fig. 4 for the sake of clearness.

After the parts have been assembled as shown in Fig. 2 the first step of the seaming operation is performed, substantially as in the well known manner. In this operation a forming roller 19 40 engages with the outer surface of the flange 16, curling the same inwardly. In this forming operation, the body flange 14 is bent downwardly in the form of a lip presenting a cylindrical outer face and the curled edge portion 17 is bent inwardly and upwardly between the flange 14 and the side wall 8.

In the next and final sealing operation shown in Fig. 4, a roller 20 having a specially shaped forming groove 21 in its periphery is applied to the now rounded flange 16 of the end member so as to force the several parts tightly together, with the terminal portion 17 between the wall 8 and the flange 14, and with the flange 14 interlocked tightly between the cover flange 55

18 and its terminal portion 17. At the same time the bead 12 is formed, providing the annular cutter-receiving space 13. It will of course be understood that in accordance with common practice an inner driving member or chuck (not shown) engages with the annular vertical wall portion 15 so as to cooperate with the outer rolls in the formation of a tight seam.

In accordance with the present invention the can is opened by inserting a cutter through the layer of metal forming the bottom wall 12^a of the annular space 13 and relatively moving the cutter and can so as to effect a circumferential severance of the seam at a point below the top 15 thereof thereby forming a friction slip cover for the can. To facilitate removal of the cover the outer severed edge portion of the seam is forced outwardly with a circumferentially expanding movement, breaking the seal formed 20 by the gasket 18. The term "bottom" as applied to the wall of the bead is used for the sake of brevity in the present description and claims to designate the wall 12^a on the bead which lies at the end of the bead adjacent the body of the 25 can as distinguished from that adjacent the end of the can.

In performing the opening operation a suitable cutting implement is employed. Such implement may take various forms, but essentially 30 the arrangement is such that as an incident to performing the cutting operation the outer severed portion of the seam is forced or spread outwardly away from the adjacent body flange 14 as shown in Fig. 6. Herein, I have shown a 35 rotary cutter 22 rotatably mounted in a bracket 23 and shiftable relative to the bracket and in a direction parallel with the side wall of the can body into and out of penetrating relation to the cutter receiving space 13.

40. The bracket 23 is guided for movement circumferentially of the can during the cutting operation, and for this purpose is formed at its upper end with a hook 24 engageable slidably with the upper and inner faces of the double seam as shown in Fig. 6, and with a pair 45 of bearing lugs 25 on opposite sides of the hook portion adapted to engage slidably with the top surface of the seam. At its lower end the bracket has a flange 26 arranged to bear upon the outer 50 cylindrical face of the can body.

The cutter 22 has a hub 27 journaled in a bushing 28 which in turn is rotatably mounted in the bracket 23. The hub 27 is arranged to be rotated manually, to impart a rotary motion 55 to the cutter, by any suitable means such as a handle 29 fixed to the outer end of the hub as by a screw 30 and suitably held against rotation relative to the hub. As shown, the handle 29 is in the nature of a double-winged key for 60 convenience in manipulation.

65. The cutter is preferably shaped (Fig. 6), to provide a beveled outer face 31 and a knurled inner face 32 perpendicular to the axis of the cutter; and formed integral with the cutter at the inner side thereof is a bearing disk 33 for engagement with the under surface of the shoulder portion 12^a of the hollow bead 12, it being observed that this bearing disk is disposed in opposed relation to the underside 24^a of the 70 hook 24 at the upper end of the bracket.

75. For the purpose of shifting the cutter bodily a predetermined distance into and out of penetrating relation to the space 13, the hub 27 thereof is mounted eccentrically in the bushing 28 as shown clearly in Fig. 6, and means is pro-

vided for rotating the bushing relative to the bracket. This means comprises in the present instance a lever 34 having at one end an enlarged portion 35 apertured to receive the hub and suitably fastened to the hub in nonrotatable 5 relation thereto. At its opposite end the lever has a handle portion 36, and the arrangement is such that in the movement of the lever from the position shown in broken lines in Fig. 5 to the full line position or through approximately 10 180 degrees, the cutter 22 is shifted from a position slightly below the shoulder 12^a of the seam through the bottom wall of the space 13 and into the position shown in Fig. 6 where it is held by the dead center action of the eccentric.

In the operation of opening the improved can, the implement is applied thereto with the lever 34 in the position shown in broken lines in Fig. 5 and with the cutter in its lowered position. Thereupon the lever 34 is operated to revolve the bushing 28 and, due to the eccentric mounting of the cutter relative to the bushing, as the lever moves into the full line position shown in Fig. 5, the cutter is forced a predetermined distance through the bottom wall of the space 13 and into the position shown in Fig. 6. Thereupon the key handle 29 is rotated, and in such rotation the knurled face 32 bitingly engages with the inner edge of the severed layer of 30 metal with the result that the implement moves circumferentially of the can body.

It will be understood that the proportions of the parts are such that as the cutter 22 is forced into cutting relation to the seam, the beveled surface 31 thereof acts upon the outer severed edge of the layer of metal penetrated, folding the same upwardly against the top wall of the bead 12. At the same time, the beveled edge portion of the cutter forces the flange 21 progressively outwardly with a wedging action to effect a circumferential expansion of the flange. Such expansion of the flange serves to disrupt the seal afforded by the gasket 18 and thus facilitates removal of the end wall in the form 45 of a removable slip cover of which the flange 21 forms the depending outer skirt or lip. It will, of course, be understood that in the drawing, and particularly in Fig. 6, the parts are shown on a substantially enlarged scale so that 50 the amount of clearance shown between the flange 21 and the adjacent body flange 14 is apparently exaggerated. In actual practice, the clearance is just sufficient to insure disruption of the seal. After the cover has been completely 55 severed, it may be replaced upon the can for reclosure purposes, with the inner flange portion 15 fitting snugly into the upper end of the body and the outer flange portion 21 encircling the body flange 14.

60. It will also be observed that in the operation of removing the end wall or cover the inner severed edge of the wall portion 12^a of the body is folded around the lower edge of the body flange 14. In the travel of the cutter circumferentially of the can, this folded edge is severed by the knurled inner face of the cutter and is serrated thereby as an incident to the pressure of the knurled face against the edge of the metal. The result is that any sharp edges which might 70 otherwise protrude are effectually eliminated. At the same time the outer edge of the severed layer of metal is folded upwardly so as to eliminate any sharp edges on the cover portion. Thus the cutter operates to fold the severed edge por- 75

tions backwardly against adjoining parts, both in the case of the body and the cover, so as to avoid danger of cutting the user.

No claim is herein made to the cutting implement shown and described, such implement being claimed in my copending application Serial No. 205,159, filed April 30, 1938.

I claim as my invention:

1. The method of removing an end wall of a can in which the end wall and the body are united in a double interlocking seam composed of a body flange and an interlocking flange on the end wall fashioned to form a narrow, outwardly protruding bead providing an annular cutter penetrable space in said seam externally of the can body, which comprises inserting a cutter through the portion of the seam forming the bottom wall of said bead and between the body flange and the adjacent flange of the end wall, relatively rotating the can and the cutter circumferentially of the can to sever the bottom of the bead, and progressively forcing the flange on the end wall outwardly away from the body flange.
2. The method of removing an end wall of a can in which the end wall and the body are united in a double interlocking seam composed of a body flange and an interlocking flange on the end wall fashioned to provide an annular space at the bottom of the seam, which comprises inserting a cutter through the bottom of the seam into said space, and, while moving the cutter circumferentially of the can, severing the bottom of the seam and simultaneously folding the inner severed edge portion of the flange on the end wall upwardly around the lower edge of the body flange.
3. The method of removing an end wall of a can in which the end wall and the body are united in a double interlocking seam composed of a body flange and an interlocking flange on the end wall fashioned to form an outwardly projecting bead providing an annular space in the bottom portion of the seam, which comprises inserting a cutter through the bottom of the seam into said space and between the body flange and the adjacent flange of the end wall, and, while moving the cutter circumferentially of the can, severing the bottom of the seam and simul-

taneously forcing the flange on the end wall outwardly away from the body flange and folding the inner severed edge portion of the end wall flange upwardly around the lower edge of the body flange.

4. The method of removing an end wall of a can in which the end wall and the body are united in a double interlocking seam composed of a body flange and an interlocking flange on the end wall fashioned to form an outwardly projecting bead providing an annular space in the bottom portion of the seam, which comprises inserting a cutter through the bottom of the seam into said space and between the body flange and the adjacent flange of the end wall, and, while moving the cutter circumferentially of the can, severing the bottom of the seam and simultaneously folding the severed edge portions of the end wall flange upwardly one against the top wall of the bead and the other against the lower edge of the body flange.

5. The method of removing an end wall of a can in which the end wall and the body are united in an upstanding double interlocking seam fashioned to form a narrow outwardly protruding bead providing an annular cutter penetrable space in said seam externally of the can body, which comprises inserting the cutting edge of a cutter upwardly through the portion of the seam forming the bottom wall of the bead, and relatively rotating the can and cutter with the cutting edge penetrating said space so as to sever the metal of the seam circumferentially.

6. The method of removing the top wall of a can in which said wall is united to the body in an upstanding double interlocking seam composed of a reversely bent flange on the body and a flange on the top wall interlocked with the body flange, which comprises forcing the cutting edge of a cutter upwardly through the bottom of the seam into a position between the body flange and the overlying layer of metal forming a part of the end wall flange so as to force said layer outwardly from the body flange, and relatively rotating the can and cutter while holding the cutter in said position whereby to sever the seam circumferentially.

CHARLOTTE A. ARNESEN.
